UNITED STATES PATENT OFFICE.

JOHN F. REEDER, OF SHELBYVILLE, ILLINOIS.

RAILWAY-CROSSING SIGNAL.

1,112,835.

Specification of Letters Patent.

Patented Oct. 6, 1914.

Application filed November 7, 1913. Serial No. 799,736.

To all whom it may concern:

Be it known that I, JOHN F. REEDER, a citizen of the United States, residing at Shelbyville, in the county of Shelby and State of Illinois, have invented certain new and useful Improvements in Railway-Crossing Signals, of which the following is a specification.

The present invention relates to improvements in railway crossing signals of the type known as visual signals and is automatically actuated by an approaching train.

The object of the invention is the improvement in certain details of construction and arrangements of parts of the operating mechanism for the warning signal, in order to more reliably and surely move the signal to danger position on the approach of a train, so that the approach of the train may be indicated at a highway crossing of the railway.

The invention consists essentially in a visual signal located at a predetermined point, as a highway crossing, which is agitated from a point some distance from the crossing, and by the passage of the wheels of a passing train over an actuating device.

In the accompanying drawings I have illustrated a complete embodiment of my invention constructed according to the best mode I have so far devised for the practical application of the principles of my invention.

Figure 1 is a perspective view of a portion of a railway showing my signal equipment in its general application thereto. Fig. 2 is a plan view of the operating mechanism of the signal device. Fig. 3 is a side elevation showing the actuating mechanism of the device.

The railway crossing signal consists of a metallic plate 1 in the form of a flag, which is adapted to be turned through an arc of 90 degrees, and swing to and fro when properly actuated. This flag is attached to the upper end of a rod or staff 2 which is secured at its lower end to the pivoted plate or lever arm 3 having a sleeve 4 fixed to the staff 2. The staff 2 is journaled to revolve in a bracket arm 5 which arm is fixed to the post 6 by means of a sleeve 7 and

set screw 8. The post is supported from a base plate as 9 fixed to one of the ties and is rigid therewith, but the bracket 5 is adjustable on the post in that it may be revolved about the post to desired position and there fixed by the set screw 8. In this manner the position of the flag 1 may be determined so that it will swing properly when actuated. The staff is revolved by 60 means of the draw rod 10 which is pivoted at 11 to the lever 3 and at its other end is pivoted to the arm 12. This arm 12 is pivoted at 13 to a plate 14, and at point 15 on the arm a cushioning device is pivoted. 65 This device comprises a spring 16 and draw rod or bar 17, the latter passed through the former and coupled to the pivot bolt 15, and the former held between the washer 18 and angle plate 19 which is perforated 70 for the draw bar and is fixed to the base plate 14. At 20 the draw bar 17 is pivoted to a pair of bell crank levers 21, 22 which are pivoted in the supporting plate and one of the levers has a wire rope or cord 23 75 shown as attached thereto. The rope 23 connects the operating mechanism with the actuating mechanism, and it extends along the railway track from the operating mechanism at the railway crossing to a distance 80 away from the crossing suitable for the location of the actuating device.

The actuating device comprises a depressible lever 24 pivoted at 25 to a supporting plate 26, and the hump 27 of the lever projects slightly above the top surface of the track 27 as shown in Fig. 3. The depressible lever 24 is connected to the rope 23 by means of a bell crank lever 28 and a link 29, which are pivotally supported in the 90 plate 30, and the spring 31 returns the lever to normal position.

In operation, the passing train depresses the depressible lever to pull on the rope 23, and the pull is transmitted through the 95 bell crank and draw bar, lever arm, draw rod and lever arm, to rotate the staff and thus swing the flag to and fro.

By this arrangement of parts the devices both of the operating mechanism and the 100 actuating device are compactly built, durable, and comparatively perfect in operation.

Having thus fully described my invention, what I claim as new and desire to secure by Letters Patent is:—

The combination with a revoluble staff 5 having a lever arm and a flag, of a rotary post and a bracket thereon to support the staff, a lever linked to the lever arm of the staff, and actuating mechanism connected to said lever arm including a draw bar and

a fixed washer thereon, a stationary bracket, 10 and a spring coiled about said draw bar between said washer and stationary bracket.

In testimony whereof I affix my signature in presence of two witnesses.

JOHN F. REEDER.
